WILLIAM M. DORAN, OF WASHINGTON, DISTRICT OF COLUMBIA, ASSIGNOR OF ONE-
THIRD TO EDWARD F. KIMBALL AND ONE-THIRD TO TILLIE McGUIRE DORAN,
BOTH OF WASHINGTON, DISTRICT OF COLUMBIA.

SOCKET FOR VACUUM TUBES.

Application filed June 18, 1926. Serial No. 116,902.

The present invention relates to improvements in vacuum tube sockets and means for connecting vacuum tubes therewith.

In the constructions of vacuum tube sockets commonly employed in radio receiving sets, the circuit terminals in the socket which co-operate with plugs on the base of the vacuum tube supported by the socket are separated or spaced laterally one from the other by open spaces. Experience has shown that many of the undesired, extraneous, sounds heard when a radio receiving set is being used, are due to eddying and stray currents passing across the spaces thus separating the socket contacts. These objectionable results can be avoided, being practically eliminated, and the quality, volume and control of signals materially improved, if means are provided whereby said socket terminals are effectually insulated one from the other.

A particular object of the present invention is to provide means whereby each socket contact will be effectually insulated from every other similar contact, while maintaining proper electrical connection with the associated prong of the tube base supported by the socket.

With this and other ends in view, the invention consists in the construction and arrangement of parts that will be hereinafter more particularly described, reference being had to the accompanying drawing, in which:—

Fig. 1 is a view, the socket being shown partially in section, of a vacuum tube socket and tube having an embodiment of the present invention applied thereto, said socket and tube being shown in separated relation.

Fig. 2 is a view, partially in section, on a slightly enlarged scale, showing the tube fitted within the socket.

Fig. 3 is a detail view of the improved base or closure for the contact end of the socket, detached.

Fig. 4 is an elevation illustrating a slightly modified form.

Fig. 5 is a detail of a means for securing the improved socket base to the body of the socket.

Fig. 6 is a detail view of one of the elements of my improved insulation means.

Referring to the drawings, in the several views of which corresponding parts are designated by like reference characters, 1 designates a vacuum tube, from the base of which 55 depend a plurality of terminal prongs 2.

It will be understood that the present invention is not limited to use with any particular type or style of vacuum tube or socket therefor, and the illustration of many of the 60 parts is purely conventional.

In the embodiment of the invention illustrated, the tube base 1 is provided with four (4) depending terminal prongs 2, each of which is designed to cooperate with a contact 3 supported by and projecting inwardly from the annular wall 5 of a tube socket. As shown, the socket contacts 3 are of spring sheet metal, each being secured to an annular flange 6 at one end of the tubular body 70 of the socket, by a suitable screw connection 7 for attachment of a circuit conductor, not shown. The socket contacts 3 shown extend radially into the space within the tubular body 5, and, normally, the inner ends of said 75 contacts are separated by a clear space, similar spaces separating the adjacent edges of the several contacts. 8 designates a closure or base for the end of the tubular socket body adjacent the contacts 3, said base being provided on one face with a boss 9, which is of such dimensions and form as to fit closely within the annular wall 5 of the socket, and in the inner face of this boss 9 are formed a plurality of sockets 10 corresponding in form and relation to the contacts 3. The sockets or grooves 10 extend radially through the periphery of the boss 9, and are of such depth that when the closure 8 is applied against the lower face of the 80 flange 6 of the socket, the inner surface of the boss will be in the plane of or slightly above the horizontal plane of the several contacts 3.

As shown, the base 8 is provided with 95 diametrically opposed thickened sections 11 which closely abut opposite sides of the flange 6 of the socket, which flange is preferably of substantially rectangular form.

As shown, apertures 12 are formed in the 100 sections 11 of the base, through which suitable fastening means may be passed to se-

cure the base to any suitable support. The base 8 may be of any suitable insulating material, rubber having been found very satisfactory.

5 When the base 8 is secured to the flange 6 of the socket body and the tube base 1 is inserted therein, the ends of the terminal plugs 2 will bear upon the socket contacts 3 and depress the latter slightly, making a 10 good electrical contact therewith, the sides and inner end of each said socket contact being, as shown and above described, separated by the portions of the insulating boss 9 filling the spaces normally separating one 15 contact from the other.

Means are also provided for effectually separating the projecting portions of the terminal prongs 2 of the tube base to substantially prevent the passage of current laterally or radially therefrom and assist in the insulation separation of the socket contacts. As shown, this means includes two washers 13, 14, each of which is provided with apertures through which the prongs 2 25 on the tube base extend, such washers being collectively of a thickness substantially equal to the length of the projecting portions of said prongs, and allowing only the extreme free ends of the prongs to project, 30 so that while the desired electric contact may be made with the socket contacts 3, there will be a body of insulation in the path of any stray current tending to pass laterally between the prongs.

35 In some instances, where the terminal prongs 2 of the tube base are relatively short, a single washer may suffice, but preferably two are employed, as shown. Such washer or washers are of any suitable compressible insulating material, such as soft rubber, and where a plurality of washers is employed, they are preferably of different degrees of compressibility. That is, the washer 13, for example, in the embodiment 40 of the invention illustrated, is relatively softer and more easily compressed than the washer 14, the result being that when the tube base is interlocked with the socket, the softer washer 13 will be considerably compressed against the inner face of the boss 9 of the socket closure and caused to effectually close the sockets in the base 8 within 45 which the contacts 3 are positioned.

The socket and tube base may be interlocked by any of the usual means. As shown, a groove 15 extends throughout the greater portion of the height of the annular wall of the socket, being provided near its upper end with a shoulder 16, and a laterally projecting pin or stud 17 on the tube base is adapted to co-operate with such groove, in the well known manner, to retain the tube in engagement with the socket and maintain the desired electrical contact 50 between the prongs 2 and contacts 3.

If desired, two or more socket closures may be formed in a single member 20, as shown in Figure 4, or an independent closure may be provided for each tube base. To insure that the recesses in the face of the 70 boss 9 of each socket base will properly register with the contacts 3, means are provided for engaging said base and socket body in only a single position. As shown, the boss 9 is provided with a short lateral projection 9a, which is adapted to fit within the groove 15 in the annular wall or shell of the socket body, and this insures that the parts can only be assembled when the recesses in the boss 9 are properly positioned 75 to receive the contacts 3.

The base member 8 may be secured to the socket body by suitable fastening means passing through apertures 8b therein, or spring clips 21, as shown in detail in Figure 85 5, may be provided, said clips including parallel members 22 and 23 adapted to respectively engage the upper face of the socket flange 6 and the lower face of the base 8.

It is believed that the invention will be 90 readily understood from the foregoing description and the drawing.

It will be seen by the invention that the base or closure for the contact end of the socket is so fitted and attached to the socket 95 as to effectually insulate the socket contacts one from the other, and positively interrupt any lateral flow of current from one contact to the other. The washers or disks on the tube base not only effectually insulate the 100 terminal prongs 2 from each other, throughout their length but co-operate with the insulation means for the contacts 3, so that the currents can only pass in the desired paths, namely, from or to the several contacts 3 105 and co-operating terminal prongs 2.

By making the closure base 8 of suitable resilient material the socket and tube will be cushioned against shocks or jars and, as before noted, the means described prevents 110 the element within the tube from being affected by extraneous sounds or stray currents passing between the terminal prongs of the tube or the socket contacts, and the result is that the volume and quality of the 115 tones obtained are materially improved.

It will be understood, of course, that many of the features of the invention could be embodied in other forms than those illustrated, and, therefore, unless specifically 120 noted in the appended claims, it is not intended to limit the invention to the exact details shown.

While the members 13, 14, are shown as being detachable from the prongs 2, they 125 might be permanently connected with the tube base or constitute a part of such base as manufactured. The embodiment of the invention illustrated is one in which the socket and tube are of constructions com- 130

monly in use in which there is normally no provision for lateral insulation of either the contacts 3 or prongs 2.

The means for insulating the contacts 3 might be included in the socket as originally manufactured instead of being applied as a detachable closure.

I claim:—

1. A vacuum tube socket comprising a tubular body, adapted to receive a vacuum tube base and having a plurality of contacts extending laterally inward from its annular wall into position to be engaged by terminal plugs in a tube base inserted in the socket, and means cooperating with the body and including members of insulating material positioned in the spaces separating the edges and inner ends of said socket contacts, and extending into the body of the socket substantially flush with the inner faces of the contacts, for the purpose described.

2. A vacuum tube socket comprising a tubular body, adapted to receive a vacuum tube base and having a plurality of contacts extending laterally inward from its annular wall into position to be engaged by terminal plugs in a tube base inserted in the socket, and a closure for the end of the body adjacent the contacts thereof having on its inner face insulating material forming a plurality of sockets each adapted to receive one of said contacts, substantially as and for the purpose described.

3. A vacuum tube socket comprising a tubular body, adapted to receive a vacuum tube base and having a plurality of contacts extending laterally inward from its annular wall into position to be engaged by terminal plugs in a tube base inserted in the socket, a closure for the end of the body adjacent the contacts including a plurality of members of insulating material positioned to separate the adjacent edges of said contacts, and means for detachably securing said closure in position.

4. A vacuum tube socket comprising a tubular body, adapted to receive a vacuum tube base and having a plurality of contacts extending laterally inward from its annular wall into position to be engaged by terminal plugs in a tube base inserted in the socket, and a base member having a boss extending into the end of the tubular body adjacent the contacts and having formed in its inner face a plurality of sockets, that extend through the periphery of the boss, each socket receiving one of said contacts, the side walls of said sockets being of insulating material and extending between adjacent edges of any two contacts for the purpose described.

5. A vacuum tube socket comprising a tubular body, adapted to receive a vacuum tube base and having a plurality of contacts extending radially inward from its annular

wall into position to be engaged by terminal plugs on a tube base inserted in the socket, and a base member having a boss of insulating material extending into the end of said body adjacent the contacts and provided on its inner face with a plurality of sockets each receiving one of the contacts, the inner face of said boss being in a transverse plane inwardly beyond the parallel plane including the contacts.

6. A vacuum tube socket comprising a tubular body, adapted to receive a vacuum tube base and having a plurality of contacts extending laterally inward from its annular wall into position to be engaged by terminal plugs on a tube base inserted in the socket, and a socket base of insulating material having an integral boss extending into the end of said body adjacent the contacts and provided with means projecting into the spaces separating the contacts, for the purpose described.

7. A vacuum tube socket comprising a tubular body, adapted to receive a vacuum tube base and having a plurality of contacts extending laterally inward from its annular wall into position to be engaged by terminal plugs on a tube base inserted in the socket and provided at the end adjacent said contacts with an exterior lateral flange, a base member contacting with said flange and having on its inner face projecting means of insulating material that extend into the spaces between the edges and inner ends of said contacts, and means connecting said base member and flange.

8. A vacuum tube socket comprising a tubular body, adapted to receive a vacuum tube base and having a plurality of contacts extending laterally inward from its annular wall into position to be engaged by terminal plugs on a tube base inserted in the socket and provided at the end adjacent said contacts with an exterior lateral flange, a base member contacting with said flange and having on its inner face projecting means of insulating material that extend into the spaces between said contacts, and clips detachably engaging said base member and flange means connecting said base member and flange.

9. The combination with a vacuum tube having a plurality of terminal plugs projecting downward from its base, of a socket including a tubular body adapted to receive said tube base and having a plurality of contacts extending inward from its annular wall in position to be engaged by the terminal plugs on the base, insulating means within said body substantially filling the spaces between the edges of the contacts therein, a washer of insulating material, provided with apertures through which the terminal prongs of the tube base extend, inserted in the socket body with the tube base,

and means securing the tube base within the socket and holding said washer in close contact with the inner surfaces of the insulating spacing means between the socket contacts, for the purpose described.

10. The combination with a vacuum tube having a plurality of terminal plugs projecting downward from its base, of a socket including a tubular body adapted to receive said tube base and having a plurality of contacts extending inward from its annular wall in position to be engaged by the terminal plugs on the tube base, insulating means within said body substantially filling the spaces between the edges of the contacts therein, a plurality of washers, each provided with apertures through which the terminal prongs of the base extend, inserted in the socket body with the tube base, and means securing the tube base within the socket and holding the adjacent washer in close contact with the inner surfaces of the insulating spacing means between the socket contacts, for the purpose described.

11. The combination with a vacuum tube having a plurality of terminal plugs projecting downward from its base, of a socket including a tubular body adapted to receive said tube base and having a plurality of contacts extending inward from its annular wall in position to be engaged by the terminal plugs on the tube base, insulating means within said body substantially filling the spaces between the edges of the contacts therein, a plurality of washers, each provided with apertures through which the terminal prongs of the tube base extend, in-

serted in the socket body with the tube base, said washers differing in degree of compressibility, and means securing the tube base within the socket and holding the adjacent washer in close contact with the inner surfaces of the insulating spacing means between the socket contacts, for the purpose described.

12. The combination with a vacuum tube having a plurality of terminal plugs projecting from its base, of a socket including a tubular body adapted to receive said tube base and having a plurality of contacts positioned to bear against the free ends of the plugs on the tube base when the latter is within the socket, and insulating material within the tubular body of the socket, adjacent the contacts thereon and separable from said body, for obstructing the passage of current laterally between said contacts in the socket and between the said prongs on the tube base.

13. An attachment for vacuum tube sockets comprising a base adapted to be applied against the end of a vacuum tube socket adjacent the contact terminals thereof and having a boss of insulating material adapted to extend into the body of the socket into the space separating the inner ends of the contact terminals of the socket to which the attachment is applied and provided in its face with a plurality of recesses each adapted to receive one of said contact terminals.

In testimony whereof I have hereunto set my hand.

WILLIAM M. DORAN.
